COMBINATION LOCK

Olof Alfred Hage, Lerum, Sweden

Application March 29, 1949, Serial No. 84,042
In Sweden January 13, 1949

8 Claims. (Cl. 70—316)

1

The present invention refers to combination locks for safes for instance of the type shown in the U. S. Patent No. 2,104,516. The object of the invention is to improve the efficiency of combination locks and simplify the construction, thus reducing the possibility of incorrectnesses.

In locks of said type the lock spindle extends through the door and the tumblers of the lock are turned by means of an arm or the like attached to the spindle. When adjusting the tumblers for unlocking the lock, notches in the tumblers are brought into position underneath a cross bar which cross bar being swung into said notches permits a free displacement inwardly of the bolt.

The somewhat complicated construction of such locks has made the proper functioning dependent upon the exact arrangement of many parts. This is an inconvenience which has been reduced by the present invention, by which the lock construction has been simplified, the moving of the parts rendered more quiet and the function more steady and sure.

The invention is principally characterized by the provision in a lock of said type of such a combination of the tumblers and their drivers that the tumblers and drivers are coupled laterally in pairs and rotatably mounted in a row on one and the same bearing.

The invention is specifically characterized by the provision of disengageable means coupling the tumblers and drivers in pairs so they can move together during a locked controlling operation and includes means mounting the tumblers for displacement transversely of the axis of the drivers to uncouple the tumblers and drivers permitting movement of the drivers relative to the tumblers whenever the combination of a lock is to be changed.

In the accompanying drawing one embodiment of the invention is illustrated by way of example. Figs. 1-3 show an inner lock device with appertaining parts adapted for provision at the inner side of the door. Fig. 1 is a view of the device viewed from the inner side of the door with the lock in locked position, the cover plate and the outermost washer around the spindle being removed. Fig. 2 is a section on line II—II in Fig. 1. Fig. 3 is a view similar to Fig. 1, the parts of the lock being adjusted to unlock the lock, with only such parts designated which have altered positions with reference to their positions in Fig. 1. Fig. 4 is a side view on a reduced scale of a tumbler and its mounting means, Fig. 5 a cross section thereof on the line V—V in Fig. 4, and Fig. 6 is an end view thereof.

2

The housing includes a bottom or base plate 1 provided with holes 2 for screws that secure the bottom plate to the inside of the door, and side walls 3 and 4 with slots that receive cover plates 5 and 6. The bottom plate 1 is formed with a hub 7 and is provided with bosses 8, 9, 10, 11 on the inside.

On the bottom plate 1 is arranged a vertically movable slide 12. This slide has three extending legs 13, 14, 15 at the side of each other, of which the two outermost 13, 15 are directed upwards and the middle one 14 bent to axial direction relative to the hub 7. A pin 16 is attached to the slide. The slide is guided by the bosses 10, 11 as well as by the hub 7 which is situated between the legs 13, 15.

Against the slide 12 rests a returning member for the tumblers, said member being rotatably mounted on the hub 7. The returning member 20 has the shape of a disk 17 with a radial arm 18 which is bent to axial direction. The disk 17 consists of two half circle segments, the one half circle of such a small radius that the leg 14 of the slide 12 is of no hindrance for the turning of the returning member as to be seen in Fig. 1.

The blocking parts of the lock are the tumblers, the construction of which is clearly to be seen in Figs. 4-6. Each tumbler consists of an outer ring 19 and an associated inner mounting ring 20, the outer ring is rotatably mounted on the inner ring and the inner ring movably mounted on the hub 7 which passes through a central oblong opening 21 therein. This opening, which is elongated downwards provides that the inner ring with the outer ring thereon can be displaced transversely of the hub or bearing axis and this movement is upwards in reference to the hub. This transverse displacement is to be effected when the lock is to be adjusted for a new combination. In order to make this displacement possible the leg 14 of the slide 12 is inserted through additional aperture 22 in each inner mounting ring. The operation for changing the combination will be described in detail hereinafter.

45 The tumbler rings which constitute each of the outer rings 19 are pressed out adjacent their periphery so as to provide a portion on each outer ring that is displaced as shown in the drawings to lie in a plane spaced from and parallel with the plane that contains the inner mounting ring. This displaced portion has a radial notch 23 extending inwardly of the perimeter thereof to define a gate and the displaced portion further is provided with a radial tooth 24 that is inwardly directed toward the axis and which tooth has an

axis that is the same as the axis of the notch or gate. This displaced portion 27 of the outer ring is further cut-away to provide slits 25, 26 between the surface of the ring and the inner surface of the displaced portion 27 as is apparent from Figure 5.

The drivers for the tumblers consist of disks rotatably mounted on the hub 7. In the illustrated lock there are three drivers, and they are respectively provided with two radial arms 29, 30 and 33, 34 and 35, 36. The segmental portion provided between the arms is a toothed circle segment 31 with serrations defining teeth and tooth spaces 32. The portion of each driver opposite said toothed segment has the shape of another segment of such a small radius that the leg 14 of the slide 12 is of no hindrance during the turning of each driver a certain angle.

Intermediate washers 37 are mounted on the hub 7 at both sides of the tumblers between the tumblers and the drivers and have the shape of circular disks. The leg 14 of the slide 12 extends through a rectangular aperture 38 in each washer preventing them from being turned, and the aperture has the same width as the leg but is of such a great height that the movement of the slide and the leg upwardly is not blocked. The outermost washer has the upper edge cut off so that the tooth spaces in the outermost tooth segment 31 can be seen at the mounting of the lock onto the door.

The tooth 24 of each tumbler meshes with one of the tooth spaces 32 of the corresponding driver. In such a way the tumblers and the drivers are coupled in pairs and are rotatably mounted on the same centre. In the embodiment shown the tumblers and the drivers are coupled laterally in pairs rotatably mounted in a row on a common bearing constituted by the hub 7. The washer 37 between the tumbler and its driver is situated in the space 28.

To move the tumblers in order to displace them by means of the drivers an angular arm 39 provided with an inwardly directed radial projection 41 is by means of a central sleeve 40 inserted into the hub 7 and mounted on the lock spindle 42, the sleeve being attached thereto by a pin 43 or in any other suitable way.

The lock bolt 44 is situated in the upper portion of the lock housing and is constituted by the inner flange of an U-shaped bar the other flange of which serves for the operation of the bolt. Said bolt is movable in an opening 46 in the side wall 4 and guided in a channel in the bosses 8, 9. It is held in horizontal position by the cover plate 5. The bolt 44 is provided with a Z-shaped aperture 47 with two inclined edges 48, 49. The flange 45 of the bolt abuts against the side wall 4 and limits in such a way the outward movement of the bolt and this flange 45 is provided with a notch 50.

A member 51 is mounted for a vertical straight lined movement between the bosses 8 and 9. The lower portion of the member has a somewhat reduced thickness and constitutes a cross bar 52 situated above all of the tumblers. The member 51 is provided with a boring for a pin 53 which extends through the aperture 47 of the lock bolt 44. The cross bar 52 receives its vertical movement by means of the inclined edges 48, 49 when the lock bolt 44 is moved horizontally.

A bottom slide 54 rests slidably on the lower cover plate 6 and two extensions 55, 56 from the rear edge of said slide underlie the bosses 10, 11.

The ends of the bottom slide and a portion of the rear edge thereof are bent upwards constituting flanges 57, 58, 59. The flange 58 of the rear edge is provided with a Z-shaped aperture 60 with inclined edges 61, 62. The walls of this Z-shaped aperture thereby constituting a direction controlling track. The foremost edge of the bottom slide 54 is guided by guides 63, 64. A pin 16 attached to the vertical slide 12 extends through the aperture 60 so that the vertical slide 12 receives a vertical movement when the bottom slide 54 is moved horizontally.

The lock portion situated on the outside of the door to manipulate the lock spindle is not shown in the drawing as the spindle is operated in the same manner as or analogous with the lock device of the U. S. Patent No. 2,104,516. The spindle and the angular arm 39 are moved by means of the usual turning knob in turning movements between stepwise axial movements. At the stepwise movements the projection 41 of the angular arm 39 will be successively adjusted into positions in front of the arms 36, 34, 30 of the drivers 31, and at the turning movements of the spindle the projection 41 will catch the drivers and bring the tumbler rings 19 to their right positions. After the last axial step the projection 41 is brought into coaction with the lock bolt to move the same.

The unlocking of the lock will be carried through in the following manner.

From the locked position as seen in Fig. 1 the spindle 42 is drawn outwards as far as possible and the projection 41 of the angular arm 39 will then be brought to stop in the front of the arm 36 of the innermost driver 31. The spindle is now turned counterclockwise in Fig. 1 and the projection 41 will catch and move the arm 36. The outer tumbler ring 19 coupled to the corresponding tooth segment of the driver will participate in this turning, so that the notch 23 of the tumbler ring will be brought into position beneath the cross bar 52 when the turning is stopped by a blocking device of the outer lock not shown. At the beginning of the movement of said driver 31 the arm 35 opposite the arm 36 and belonging to the same driver 31 has engaged the arm 18 of the returning member 17 and moved the returning member the same turning angle. The spindle is now turned clockwise in Fig. 1 and pushed inwardly one axial step, so that the projection 41 is brought into position in the front of the arm 34 of the next driver 31, and the movement described above is repeated and then repeated as many times as the number of the tumblers, thus bringing the notches 23 of all of the tumblers into position beneath the cross bar 52, if the right combination has been used. In the case that an incorrect combination has been used one or more of the notches 23 are not placed beneath the cross bar. After the last movement of the spindle the projection 41 of the angular arm 39 will have passed all the tumblers as seen in Fig. 2.

After the last axial movement the spindle is turned counterclockwise in Fig. 1, so that the angular arm 39 catches the notch 50 of the flange 45 and drives the flange with the lock bolt 44 inwards, whereat the inclined edge 49 forces the pin 53 downwards together with the cross bar 52. If all the notches 23 are in right position beneath the cross bar 52 the downward movement is not blocked and the movement of the bolt is carried through to unlocked position. If however one or more of the notches 23 are

not directly beneath said cross bar, as will be the case if an incorrect combination has been used, the downward movement of the cross bar 52 is blocked and the inward movement of the bolt is checked.

The locking of the lock is carried through in the following way.

In the unlocked position of the lock as seen in Fig. 3 the angular arm 39 has its projection 41 inserted into the notch 50 of the lock bolt 44. The spindle is now turned clockwise and at this movement the lock bolt 44 is pushed outwards and the edge 48 of the bolt will lift the pin 53 and therewith the cross bar 52 up out of notches 23, so that the tumbler rings 19 are freed. At the continued turning the angular arm 39 catches the arm 18 of the returning member 17 so that this member successively abuts against the arms 35, 33 and 29 and turns all the drivers 31 as well as the tumbler rings 19 coupled thereto back to the initial position. This movement is stopped when the arms 29, 33 and 35 engage against the boss 8, and the lock is locked as shown in Fig. 1.

The adjustment of the lock for a new combination is carried through in the following manner.

From the unlocked position of the lock in Fig. 3 the spindle is turned until the lock bolt 44 has reached the position in Fig. 1. Thus the cross bar 52 has been lifted out of the notches 23, but these are yet situated beneath the cross bar. Now the flange 57 with the bottom slide 54 is pushed to the left until the flange is stopped by the side wall 3. During this movement the inclined aperture edge 61 in the flange 53 of the bottom slide has lifted the pin 16 and thus also the vertical slide 12 attached thereto. This lifting movement causes the tumblers to move vertically as the leg 14 of the vertical slide is inserted through the mounting rings 20 of the tumblers, with the result that the teeth 24 of the tumbler outer rings 19 of the tumblers are disengaged from the tooth spaces 32 of the drivers 31. The spindle now is turned in the direction for the locking of the lock and by this movement the drivers 31 with their tooth segments and arms are brought into the position shown in Fig. 1, but the tumbler outer rings 19 have not been turned.

Now the lock is operated in the same way as when unlocking the lock and the new combination is used. After this adjustment of the drivers and their tooth segments the flange 59 with the bottom slide 54 is pushed to the right until the flange is stopped by the side wall 4 as shown in Fig. 1. During this movement the pin 16 has been forced downwards by the inclined edge 62, so that the vertical slide 12 has been lowered until it has reached the lower position in Fig. 1, and the teeth 24 of the tumbler outer rings have again been engaged to the tooth spaces 32. The lock is now adjusted for the new combination. When the lock then is locked the arms 29, 33, 35 turn each tumbler ring 19 and their notches 23 a certain angle, and to unlock the lock each arm 30, 34, 36 must be turned exactly the corresponding angle, and these angles are defined by the new combination.

The details of the arrangement may obviously be subjected to different modifications within the scope of the appended claims. Each tumbler ring can be provided with more than one tooth. For the lifting of the tumblers other means can be used than the slides described above, and the lock bolt can be pushed into position by another element than the angular arm 39.

It is therefore clear that the present invention provides in the broader aspect and in a combination lock of the type in which a movable bolt controlling pin is cooperable with alignable gates or notches in tumblers, a tumbler and driver arrangement that includes a fixed hollow bearing, a plurality of axially aligned tumblers having the gate defining notches therein surrounding the bearing, a plurality of drivers are rotatably mounted on the bearing in alternating relationship with the tumblers and means are provided that mount the tumblers for rotation about the bearing. The aforescribed tooth engagement between the tooth 24 and the selected tooth on the adjacent driver constitute disengageable means that laterally couple the tumblers and drivers in pairs and an axially and rotatably movable spindle that is coaxially positioned with respect to the bearing and includes an arm means extending therefrom and cooperable with the arms on the drivers for moving the drivers and thereby the tumblers coupled thereto in a lock controlling operation. The mounting means provide for transverse movement of the tumblers relative to the drivers so that the coupling means can be disengaged permitting the drivers to rotate relative to the tumblers when it is desired to change the combination of the lock. As disclosed in the drawing the tumbler and drive arrangement also includes the slide arm 14 which passes through the aligned additional apertures 22 in the mounting rings so that when this slide is displaced all of the mounting rings and tumblers are moved transversely of the axis of the bearing to disengage the toothed engagement. Each of the drivers are segmental in plan and includes one circumferential edge that is so spaced with respect to the axis of the hub that the movement of the arm 14 with the movement of the slide is not blocked by this edge of each driver. The diametrically extending arms on each driver extend from the opposite terminal ends from the circumferential edge and it is clear that these arms are movable through arcs on opposite sides of the arm 14 and swing responsive to manipulation of the spindle. Additionally it is to be noted that a second slide member having a Z-shaped aperture therein, the walls of which define direction controlling track, is mounted for movement transversely of the axis and direction of movement of the first slide member so that a pin carried by the first slide that extends within the aperture of the second slide is displaced responsive to transverse movement of the second slide and the displacement of this pin effecting corresponding displacement of the first slide and its arm 14 together with the mounting means for the tumblers and the tumblers to disengage the toothed engagement connecting the tumblers and drivers in pairs permitting manipulation of the drivers while the tumblers remain stationary in order to change the point of re-engagement of the tumblers with the drivers upon reverse manipulation of the slides so that the combination of the lock can be changed.

What I claim is:

1. In a combination lock of the type in which a movable bolt controlling fence is cooperable with alignable gates in tumblers, a tumbler and driver arrangement including a fixed hollow bearing, a plurality of tumblers having gate defining notches therein surrounding said bearing, a plurality of drivers rotatably mounted on said bearing in alternating relationship with said tumblers, means mounting the tumblers for rotation about

the bearing, means laterally coupling the tumblers and drivers in pairs, an axially and rotatably movable spindle coaxially positioned with respect to said bearing and having an arm extended therefrom cooperable with said drivers for selectively moving the drivers and thereby the tumblers coupled thereto in a lock controlling operation, and said mounting means including means providing for transverse movement of the tumblers relative to the drivers to disengage the coupling means coupling the tumblers and drivers in pairs so that the drivers can be rotated relative to the tumblers for changing the combination of the lock.

2. A tumbler and driver arrangement for a combination lock as defined in and by claim 1 in which the coupled tumblers and drivers constitute pairs of members and teeth extending from one member of each pair, the other member of each pair having teeth receiving apertures therein and said teeth detachably engaging said apertures.

3. A tumbler and driver arrangement for a combination lock as defined in and by claim 2 in which the teeth extend from the tumblers, the drivers have the teeth receiving apertures therein and means for transversely moving the means mounting the tumblers so that the teeth on the tumblers can be disengaged from the apertures in the drivers.

4. A tumbler and driver arrangement for a combination lock as defined in and by claim 1 in which each tumbler comprises an outer ring and said mounting means comprising an inner ring, said inner ring having an oblong aperture in the center thereof, said inner rings being mounted on said bearing and said outer rings being rotatably mounted on said inner rings and shiftable means cooperable with said inner rings and in one position holding the same stationary while permitting rotation of the outer rings relative to the inner rings and when shifted transversely displacing the inner rings and the outer rings mounted thereon.

5. A tumbler and driver arrangement for a combination lock as defined in and by claim 4 in which the inner rings each have an additional aperture therein, said apertures being aligned with each other, said shiftable means including a slide member mounted for movement transversely of the axis of said bearing, a leg extending from said slide member in a direction parallel with the axis of said bearing and through said aligned apertures in the inner rings whereby movement of said slide transversely of the axis of said bearing displaces the inner ring and thereby the tumblers.

6. In a combination lock a housing, a hub extending inwardly from one wall of said housing and terminating within the housing, a spindle coaxially disposed within said hub and rotatably and axially movable with respect thereto, an angular arm extending radially of said spindle and including two legs, one extending parallel with the axis of the spindle toward the wall of the housing from which the hub extends, the other leg constituting a radial extension of the spindle and having such length as to dispose the first-mentioned leg in substantial spaced relation with respect to the hub, a plurality of tumblers having gate defining notches therein surrounding said hub, a plurality of drivers rotatably mounted on said hub, said tumblers and drivers constituting disc members and being disposed in lateral alternating relationship on said hub, mounting means for mounting the tumblers for rotation

about said hub, disengageable means laterally coupling the tumblers and drivers in pairs, said mounting means constituting ring members having oblong central apertures therein mounting the same on said hub, said central apertures permitting displacement of the ring members and tumblers transversely of the axis of the hub, said ring members having additional aligned apertures therein each having an inner wall, said drivers being segmental in plan and including a circumferential edge so spaced with respect to the axis of the hub as to be inward of the inner wall of said additional apertures in the ring members, said edge having opposite terminal ends, a slide member slidably mounted on the said wall of the housing for movement transversely with respect to the axis of the hub, said slide member having an arm extending outwardly thereof parallel with the said axis of the spindle and passing through the aligned additional apertures in the ring members so that movement of the slide member transversely of the hub moves said ring members and tumblers relative to the drivers to disengage the coupling means between the drivers and the tumblers to permit changing the combination of the tumblers, said drivers having diametrically extending arms projecting outwardly thereof, from the opposite terminal ends of said circumferential edge, the opposite arms of each driver being movable through respective arcs on opposite sides of said arm on the slide member, and the arc described by said circumferential edge of each driver being inward of the limit of movement of said arm on the slide member so that displacement of the arm extending from the side member and thereby displacement of the tumblers is not blocked by the drivers, and a lug carried by the said leg of the said angular arm that is parallel to the axis of the hub, said lug projecting toward the axis of the spindle and having such length as to cross an arc described by the outer ends of the arms extending from the drivers, so that said lug is selectively cooperable and engageable with the arms of the drivers for displacing the same and thereby the tumblers coupled therewith upon selective axial and rotary movement of said spindle.

7. In a combination lock as defined in and by claim 6 wherein each said ring member comprises an inner ring having the oblong central aperture therein movably mounting the same on said hub in a manner permitting transverse movement relative to the hub and each said tumbler comprises an outer ring rotatably mounted on said inner ring, a portion of said outer ring being displaced so as to lie in a plane spaced from and parallel with the plane containing said inner ring, said displaced portion having a notch extending inwardly of the perimeter thereof to define a gate and said displaced portion further having a tooth extending inwardly thereof with the axis of the tooth being the same as the axis of the notch, each said driver comprising an apertured segmental disc having serrations on a portion of the circumference thereof constituting teeth selectively engageable by the tooth on the displaced portion of said outer ring, said toothed engagement constituting the disengageable means for coupling the tumblers and drivers laterally in pairs and the movement of said inner rings and thereby the tumblers transverse of the axis of said hub disengaging the teeth on the tumblers from the teeth on the drivers to permit rotation of the drivers relative to the outer rings whenever the combination of the lock is to be changed.

8. In a combination lock as defined in and by

claim 6 and a second slide member having an aperture therein the walls of which define a direction controlling track, said slide being movable transversely of the axis of said first-mentioned slide, a pin carried by said first-mentioned slide and extending within the aperture of said second-mentioned slide whereby upon transverse displacement of said second slide said pin and thereby said first slide are displaced transversely of the axis of the hub.
